UNITED STATES PATENT OFFICE.

JOHN BIRCH LEONARD, OF MEMPHIS, TENNESSEE.

HOLLOW BLAST-BURNER FOR FURNACES.

1,158,939.

Specification of Letters Patent.

Patented Nov. 2, 1915.

Application filed May 19, 1915. Serial No. 29,159.

To all whom it may concern:

Be it known that I, JOHN B. LEONARD, a citizen of the United States, residing at Memphis, in the county of Shelby and State of Tennessee, have invented certain new and useful Improvements in Hollow Blast-Burners for Furnaces, of which the following is a specification.

5 My invention relates to improvements in hollow blast burners for furnaces.

An important object of the invention is to provide a burner of the above mentioned character, formed in upper and lower sections having air tight connections with each 10 other, which will permit of the relative expansion and contraction of the sections, while maintaining the joints air tight.

A further object of the invention is to provide a simple and efficient dump-door for 15 normally closing the bottom of the hollow burner and retaining it substantially air tight, and adapted to reduce the friction between the engaging parts, to the minimum.

A further object of the invention is to 20 provide a dump-door of the above mentioned character, which is simple in construction, inexpensive to manufacture, and durable.

A further object of the invention is to provide a burner of the above mentioned character, having its top provided with angularly and vertically arranged openings, discharging the air in divers directions, for 25 effecting a complete and thorough combustion of the fuel.

30 A further object of the invention is to provide simple and reliable means to swing or move the dump-doors.

Other objects and advantages of the invention will be apparent during the course of 35 the following description.

In the accompanying drawings forming a part of this specification and in which like numerals are employed to designate like parts throughout the same, Figure 1 is a 40 side elevation of a burner embodying my invention, parts thereof and the shell of the furnace being in section, Fig. 2 is a plan view of a burner-section, Fig. 3 is an end elevation of a plurality of burner-sections, 45 assembled, taken on line 3-3 of Fig. 1, Fig. 50 4 is a transverse sectional view taken on line 4-4 of Fig. 2, Fig. 5 is a plan view of one of the burner plates removed, and, Fig. 6 is an end elevation of the same.

55 In the drawings, wherein for the purpose of illustration is shown a preferred embodiment

ment of my invention, the numeral 10 designates a furnace casing, as a whole, having a combustion chamber 11. Above the combustion chamber is a boiler 12, and below it, 60 my improved burner 13. This burner is made up of a plurality of hollow blast burner-sections 14 arranged side-by-side in spaced relation and having asbestos 13' or the like arranged therebetween. Each 65 burner-section comprises an upper portion 15, having a top 16, preferably inclined upwardly near its forward end, as shown at 17. The side walls of the portion 15 are provided at their longitudinal edges with 70 grooves 17', preferably inverted V-shaped in cross-section, which are adapted to receive tongues 18, preferably V-shaped in cross-section and formed upon a co-acting lower portion 19. The forward end of the lower 75 portion 19 is provided with a forwardly extending flange 20, engaging and supported by a substantially Z-shaped rest 21, embedded in the front wall of the furnace, as shown. Each burner-section has its opposite 80 site ends closed, as shown.

Arranged between the forward end of the upper portion 14 and the forward wall of the furnace is a dead-plate 22, as shown. The rear end of the lower portion 19 is provided with a depending air chamber 23, 35 preferably cast integral therewith. The chamber 23 serves as a rest for the rear end of the portion 19 and is provided at its lower end with a flange 24, arranged upon 90 a brick air flue or duct 25, having air fed thereto, under suitable pressure through a pipe 26, as shown.

As more clearly shown in Figs. 1 and 4, the lower portion 19 of the burner section 95 has its bottom open from its forward end to the air chamber 23, such opening or opening bottom being normally covered by a dump-door 27. This dump-door is rigidly mounted upon a rod or rock-shaft 28, journaled 100 through bearings 29, attached to the lower end of the portion 19. As more clearly shown in Fig. 4, one edge of the dump-door 27 is transversely rounded for 105 slidable engagement with the inwardly bulging portion or fillet 30, having an inner beveled or inclined face 31. The upper surface of the dump-door 27, adjacent its opposite longitudinal edge engages with the lower rounded edge 32 of the opposite side of the portion 19, as shown. It is obvious that this construction provides means whereby the 110

dump-door 27 may have a firm and close contact with the adjacent walls of the portion 19 of the burner for providing a substantial air tight union, the rounded edges 5 of the engaging parts preventing undue friction. When the ashes or deposits accumulate upon the outer surface of the dump-door 27, it is swung to the inclined position, so that they readily slip off of it.

10 Rigidly connected with the forward ends of the rods or rock-shafts 28 are depending cranks 33, having pivotal connection, as shown at 34, with a reciprocatory bar 35. This reciprocatory bar is provided with an 15 upstanding recess or opening 36, receiving and engaging a roller 37, connected with the upper end of a shifting crank 38. This shifting crank 38 is rigidly mounted upon a rock-shaft 39, suitably journaled and ex- 20 tending through the forward wall of the furnace and having its outer end formed square in cross-section, for detachably receiving a key-crank 40 for turning it.

The top 16 of each burner-section is pro- 25 vided with spaced pairs of longitudinal openings 41, between the ends of which are arranged transverse openings 42. The open- 30 ings 41 and 42 are preferably identical, and each opening is substantially trapezoidal in transverse and longitudinal sections, with its side and end walls inclined or flaring up- 35 wardly. Arranged within each of these openings is a plate 43, disposed longitudinally or transversely of the top 16. Each 40 plate 43 is trapezoidal in transverse and lon- 45 gitudinal sections and tapers downwardly, and is substantially smaller in transverse and longitudinal dimensions than the opening. Each plate 43 is provided with later- 50 ally extending lugs or members 44, prefer- 55 ably formed integral therewith, and having beveled ends 45, to engage with the beveled walls of the openings, whereby the plate is held spaced from the walls of the opening, 60 the ends of the plate being also spaced from the end walls of the opening, providing a 65 preferably rectangular air passage 43', dis- 70 charging the air upwardly and outwardly. The top 16 is also provided with vertical 75 longitudinal air openings 48, arranged be- 80 tween the longitudinal openings 41, as shown. By the alternate arrangement of the longitudinal and transverse openings 85 43', it is obvious that the air passes up- 90 wardly into the combustion chamber, in various upwardly inclined directions, and the air passing vertically through the open- 95 ings 48, becomes thoroughly mixed with the incoming air through the openings 43', in 100 the presence of the gases or products of combustion, for effecting a complete con- 105 sumption of the fuel.

Each plate 43 is provided with transverse 110 opening or openings, receiving bolt or bolts 115 46, preferably arranged therein while the

plates are being cast, such bolts having connection at their lower ends with a transverse locking bar or bars 47, engaging beneath the top for clamping the plate in position.

In the use of the burner, the furnace may 70 be started without the employment of the forced draft, as sufficient air will pass through the openings in the top 16, to permit of the combustion of the coal or fuel, for this purpose. When steam is gotten up, 75 an engine is driven which in turn drives a fan, supplying air under suitable pressure, into the hollow burner. This air passes vertically through the openings 48 and upwardly at inclined angles through the open- 80 ings 43'.

It is to be understood that the form of my invention herewith shown and described is to be taken as a preferred example of the same, and that various changes in the shape, 85 size, and arrangement of parts may be resorted to without departing from the spirit of the invention or the scope of the subjoined claims.

Having thus described the invention, I 90 claim:—

1. In a hollow blast burner for a furnace, a hollow burner-section having an opening in its bottom and one side thereof provided with an interior vertically inclined surface 95 extending inwardly toward the lower end of the side, and a dump-door arranged within the opening in the bottom of the hollow burner-section and having one edge disposed to contact with the interior vertically inclined surface of the hollow burner-section for increasing the degree of contact between these elements as such edge is moved downwardly toward the lower end of said inclined surface, said dump-door having its 100 opposite edge portion arranged beneath the opposite side of the hollow burner-section to contact with the lower end of such opposite side, substantially as described.

2. In a hollow blast burner for a furnace; 110 a hollow burner-section having an opening in its bottom and one side thereof provided with an interior vertically inclined surface extending inwardly toward the lower end of the side; a dump-door arranged within the 115 opening in the bottom of the burner-section and extending substantially throughout the entire length of the opening with one edge thereof arranged to contact with the interior vertically inclined surface for increasing the 120 degree of contact between these elements as such edge is moved downwardly toward the lower end of said inclined surface, said dump-door having its opposite edge ar- 125 ranged beneath and projecting outwardly beyond the lower end of the opposite side wall of the burner-section; and means to swing the dump-door, upon its longitudinal axis.

3. In a hollow blast burner for a furnace; 130

a hollow burner-section having side walls with one side wall projecting downwardly beyond the other for a substantial distance and provided with an interior vertically inclined surface extending inwardly toward the lower end of such side wall, the opposite side wall having its lower edge rounded; a dump-door arranged within the open bottom of the burner-section between the side walls and extending substantially throughout the entire length of the open bottom, said dump-door having one edge rounded and adapted to contact with the interior vertically inclined surface for increasing the degree of contact between these elements as such edge is moved downwardly toward the lower end of said inclined surface, said dump-door having its opposite edge portion arranged beneath the rounded edge of the other side wall to contact therewith; and means to turn the dump-door upon its longitudinal axis.

4. In a hollow blast burner for a furnace; a hollow burner-section having a top provided with spaced pairs of longitudinally extending openings and transverse openings arranged alternately between the pairs of longitudinal openings; and plates arranged within the openings and spaced from the walls thereof for forming therewith upwardly discharging air passages.

In testimony whereof I affix my signature in presence of two witnesses.

JOHN BIRCH LEONARD.
